UNITED STATES PATENT OFFICE.

JAMES H. W. MARRIOTT, OF BALTIMORE, MARYLAND.

DESIGN FOR A POST-OFFICE CABINET.

SPECIFICATION forming part of Design No. 29,636, dated November 8, 1898.

Application filed August 8, 1898. Serial No. 688,112. Term of patent 8 $\frac{1}{2}$ years.

To all whom it may concern:

Be it known that I, JAMES H. W. MARRIOTT, a citizen of the United States, residing at Baltimore, in the State of Maryland, have invented and produced a new and original Design for Post-Office Cabinets, of which the following is a specification.

The design of the cabinet is shown in the accompanying drawing.

The general outline or elevation of the cabinet is rectangular and embraces two series of boxes, a general-delivery window intermediate of the two series, a "money-order" window at one end, with an outer shelf below the window, and a projecting cornice at the top, comprising two lower parallel or-

namental courses, a plain molding above said two courses, and a top expanding course having on its front a row of inclined scroll-leaves with a horizontal straight-line edge above them, as shown.

Having thus described my invention, what I claim is—

The design for a post-office cabinet, as herein shown and described.

In testimony whereof I affix my signature in the presence of two witnesses.

JAMES H. W. MARRIOTT.
